MAGNETIC RECORDING APPARATUS

Leland B. Greenleaf, Elkhart, Ind., assignor to
 C. G. Conn, Ltd., Elkhart, Ind., a corporation
 of Indiana

Application December 1, 1944, Serial No. 566,106

9 Claims. (Cl. 242—54)

1

This invention relates to magnetic recording apparatus and more particularly to a reel or spool construction for detachable connection to a magnetic recorder or reproducer.

One of the objects of the invention is to provide a magnetic recording apparatus in which a reel or spool may be quickly and easily attached to and detached from the apparatus and in which wire carried by the spool is fully covered and protected when the spool is detached from the apparatus.

Another object is to provide a spool for magnetic recording apparatus in which wire on the spool is covered by a simple cover strip engaging the spool flanges.

Still another object is to provide magnetic recording apparatus in which a cover strip on a spool is opened and held away from the spool during operation of the apparatus.

A still further object is to provide magnetic recording apparatus in which the apparatus is controlled to start at the same time that the cover on the spool is disengaged therefrom.

The above and other objects and advantages of the invention will be more readily apparent from the following description when read in connection with the accompanying drawing, in which—

Figure 1 is a partial sectional view illustrating one form of apparatus embodying the invention;

Figure 2 is a partial plan view of a recording apparatus;

Figure 3 is a partial plan view of the apparatus with the spool removed; and

Figure 4 is a partial section of an alternative construction.

The apparatus as shown in Figure 2 may be utilized for making recordings magnetically on wire or for reproducing previously made recordings from the wire. In the apparatus illustrated, a casing or housing 10 is adapted to contain a driving motor as well as various electrical devices such as amplifiers, speakers or the like. The motor drives a driving pulley 11 over which a wire 12 passes to be driven by the pulley at a substantially constant speed. The wire is carried by a supply spool 13 detachably mounted on a central shaft 14 and is wound on a take up spool 15 beneath and concentric with the supply spool 13. The take up spool is carried by a sleeve 16 concentric with the shaft 14. The shafts 14 and 16 are driven during operation of the apparatus thru a friction driving mechanism or the like, which will permit slight variations in the shaft speed to compensate for the changing reel diameters as the wire is wound onto or unwound from

the spools. The take up reel 15 is permanently attached to the apparatus while the supply reel may be quickly attached to and detached from the apparatus by sliding it over the shaft 14, a spring detent 17 being provided yieldingly to hold the reel on the shaft.

Wire unwound from the reel 13 passes thru a level wind guide 18 over an idler pulley 19. The wire then goes thru a recording or reproducing head 20 and over the driving pulley 11. After leaving the driving pulley 11 the wire passes over a second guide pulley 21 which is held against the wire by a spring 22 to maintain it under substantially constant tension. A second level wind device 23 guides the wire onto the take up spool 15. An indicator 24 may be provided geared to one of the shafts 14 or 16 to indicate the length of wire which has been fed thru the machine.

In order to cover and protect wire on the supply spool 13 when it is detached from the machine, a resilient cover strip 25 is provided which is adapted to encircle the spool 13. The cover strip may be made of any desired material but is preferably of spring steel or the like and is normally of a smaller diameter than the reel so that it will engage tightly against the flanges on the reel. As shown, circumferential grooves 26 may be provided adjacent the edges of the cover strip to fit over the reel flanges and hold the strip firmly in place thereon. The strip is of such a length that when it engages the reel its ends will overlap slightly and one end of the strip is rolled back on itself as indicated at 27 to provide a transversely extending eye or socket.

In order to move the cover strip away from the spool when it is on the apparatus the apparatus carries a series of bell crank levers 28 pivoted at their centers. One arm of each bell crank lever carries at its outer end an upwardly extending pin or button 29 adapted to engage the lower edge of the cover strip 25 when the spool is placed on the apparatus. One bell crank lever as shown at 31 is formed with its legs at a different angle than those of the levers 28 and carries at the outer end of one arm an elongated pin 32 adapted to enter the socket 27 when the spool is placed on the machine.

The levers 28 and 31 are adapted to be moved simultaneously by means of a rotatable cam plate 33 formed in its circumference with a series of inwardly extending slots 34. Pins on the levers 28 and 31 fit into the slots 34 as shown so that when the plate 33 is turned the levers will be rocked. Preferably notches 35 are formed in the plate to receive the ends of the levers 28 which

carry the pins 29 when these ends of the levers are in their innermost positions. The plate 33 may be turned by a handle 36 extending therefrom in a position to be engaged by an operator.

With the plate 33 and the levers in the position shown in Figure 3, the pins 29 and 32 are in their radially innermost positions in which they will fit into the adjacent edge of the cover strip 25. When the plate is turned clockwise as seen in Figure 3, the levers will all be rocked to move the cover strip away from the spool as shown in Figure 2. It will be noted that the lever 31 due to its mounting and to the angle of its slot 34 will move the end of the strip a further distance from the spool than the other levers move. This provides a relatively large gap between the ends of the strip thru which the wire can pass. Due to the engagement of the pin 32 with the socket 27, the ends of the strip are accurately positioned so that the opening will always be properly located for passage of the wire. After the wire on the supply spool has had a recording made thereon by the apparatus or has had a previous recording thereon reproduced, the wire is rewound on the supply spool. By moving the handle 36 to turn the plate 33 counterclockwise, the pins 29 and 32 on the levers will be moved inwardly thereby permitting the cover strip 25 to re-engage the flanges of the spool and enclose the wire thereon. Preferably, the end of the wire or of a leader connected to the wire is left projecting between the ends of the cover strip so that it will be engaged and held by the cover strip in a position to be attached to the apparatus when the spool is installed without requiring opening of the cover.

The motor for driving the pulley 11 and the reel shafts may be controlled by a switch as indicated at 37. Preferably the switch is connected thru a link or the like 38 to the handle 36 so that when the handle is turned to open the cover on the reel, the motor will be started. This insures that before starting the motor the cover is properly opened so that the wire will not be broken.

Figure 4 illustrates an alternative arrangement for connecting the levers 28 to the cover strip. In this construction the cover strip 39 is formed in its periphery with a series of spaced loops or the like 40 which provide transversely opening sockets spaced along the length of the cover strip. The levers 41 which correspond to the levers 28 carry elongated pins 42 which are adapted to fit into the loops 40 so that the cover strip will be pulled away from the spool. By arranging the loops 40 adjacent the central part of the strip tilting or cocking of the strip will be prevented and it will be drawn evenly away from the spool flanges.

While two embodiments of the invention have been shown and described in detail herein, it will be understood that these are illustrative only and are not intended as definition of the scope of the invention, reference being had for this purpose to the appended claims.

What is claimed is:

1. A reel structure for use with a magnetic recording apparatus comprising a flanged spool adapted to be detachably mounted on the apparatus and having straight radially extending flanges, and an elongated resilient cover strip fitting around the spool and resiliently biased into engagement with the edges of the spool flanges to inclose wire on the spool one end of the strip being formed with a transversely extending socket lying radially outside of the flanges.

2. In combination with a magnetic recording

apparatus; a flanged spool, means on the apparatus for detachably mounting the spool on the apparatus, an elongated resilient cover strip fitting around the spool and normally biased into engagement with the flanges, and means on the apparatus to engage the strip at at least three spaced points in its length; and move it radially away from the flanges when the spool is mounted on the apparatus so that the spool can turn relative to the strip.

3. In combination with a magnetic recording apparatus, a flanged spool, means on the apparatus for detachably mounting the spool on the apparatus, an elongated cover strip fitting around the spool and engaging the flanges, a series of at least three levers on the apparatus engageable with the strip at spaced points in the length thereof when the spool is mounted on the apparatus, and means to turn the levers simultaneously to move the strip away from the spool.

4. In combination with a magnetic recording apparatus, a flanged spool, means on the apparatus for detachably mounting the spool on the apparatus, an elongated resilient cover strip fitting around the spool and normally biased into engagement with the flanges, the strip being formed at one end with a socket, a series of levers on the apparatus to engage the strip at spaced points in its length when the spool is mounted on the apparatus, a pin on one of the levers to fit into the socket, and means to turn the levers simultaneously to move the strip away from the spool.

5. In combination with a magnetic recording apparatus, a flanged spool, means on the apparatus for detachably mounting the spool on the apparatus, an elongated resilient cover strip fitting around the spool and normally biased into engagement with the flanges, the strip being formed at spaced points in its length with transversely opening sockets, a series of pins movably mounted on the apparatus and adapted to fit into the sockets when the spool is mounted on the apparatus, and means to move the pins outward to move the strip away from the spool.

6. In combination with a magnetic recording apparatus, a flanged spool, means on the apparatus for detachably mounting the spool on the apparatus, an elongated cover strip fitting around the spool and engaging the flanges, parts on the apparatus engageable with the strip at spaced points in its length when the spool is mounted on the apparatus, means to move the parts to move the strip away from the spool, control means to control operation of the apparatus, and a connection between the moving means and the control means to start the apparatus when the strip is moved away from the spool.

7. In combination with a magnetic recording apparatus, a flanged spool, means on the apparatus for detachably mounting the spool on the apparatus, an elongated resilient cover strip fitting around the spool and resiliently biased into engagement with the spool flanges, parts on the apparatus engageable with the strip at at least three spaced points in its length when the spool is mounted on the apparatus and means to move the parts to move the strip away from the spool.

8. In combination with a magnetic recording apparatus, a flanged spool, means on the apparatus for detachably mounting the spool on the apparatus, an elongated resilient cover strip fitting around the spool and resiliently biased into engagement with the spool flanges, the ends of

the strip overlapping when it is in place on the spool and one of the ends being formed with a socket, levers on the apparatus engageable with the strip at spaced points in its length when the spool is mounted on the apparatus, a pin on one of the levers to fit into the socket, and means to move the levers simultaneously to move the strip away from the spool.

9. A reel construction for use with a magnetic recording apparatus comprising, a flanged spool adapted to be detachably mounted on the apparatus, and an elongated resilient cover strip fitting around the spool and resiliently biased into engagement with the spool flanges to inclose wire on the spool, the strip being formed at spaced points throughout its length with transversely extending sockets to receive operating pins.
